UNITED STATES PATENT OFFICE.

FREDERICK B. LITTLE, OF CHICAGO, ILLINOIS, ASSIGNOR TO J. C. DEAGAN, INC., OF CHICAGO, ILLINOIS, A CORPORATION OF ILLINOIS.

SOUND-PRODUCING MECHANISM.

Application filed April 2, 1920. Serial No. 370,835.

To all whom it may concern:

Be it known that I, FREDERICK B. LITTLE, citizen of the United States, residing at Chicago, in the county of Cook and State of Illinois, have invented a certain new and useful Improvement in Sound-Producing Mechanism, of which the following is a full, clear, concise, and exact description.

My invention relates to sound producing equipment and is of particular service when employed in percussion musical instruments requiring heavy actions and has for its general object the provision of an improved electrically operated action capable of properly 10 setting massive vibrant bodies into vibration.

The invention has for a specific purpose the provision of mechanism insuring the retention of the hammer of the action in its rearmost position so that the extent of the 20 forward travel of the hammer is always uniform, being in this respect an improvement upon other electric actions in which the hammers are apt to come to rest in various restored positions forward of their rearmost 25 restored positions.

The action of my invention further includes a housing for the switching mechanism and having in its formation the supporting base of the equipment.

Generally speaking, my invention is realized in a structure that is inclusive of a vibrant element, a hammer mounted to strike said element to set it into vibration, and electro-magnetic mechanism having a striking winding for moving the hammer into striking engagement with said vibrant element and also desirably having a restoring winding for withdrawing the hammer to initial position. There is a striking relay having a switch controlled thereby for opening and closing the circuit of the striking winding. The restoring winding is also preferably controlled by a relay having a switch controlled thereby for opening and closing the circuit of the restoring winding. The equipment, according to the purpose to be served, employs either or both a normally open switch and a normally closed switch.

Where the normally open switch is employed 50 it is desirably in the circuit of the restoring relay and also connected to constitute the

holding switch of an electro-magnet which is controlled from a keyboard or other suitable place. Where a normally closed switch is employed it is in the circuit of the striking relay. The aforesaid electro-magnet included in the equipment above described has an armature normally mechanically positioned to maintain the normally closed switch in its normal adjustment, said magnet serving when energized to attract its armature to open said normally closed switch and to close said normally open switch. There is also switching mechanism that is placed in one adjustment by the hammer in being restored and then serving to connect the aforesaid normally closed switch in the circuit of the striking relay and serving in an alternative adjustment that is effected by the hammer in being moved to striking position to disconnect said normally closed switch from the striking relay and to close the circuit of said magnet to open said normally closed switch and to close said normally open switch, said switching mechanism in its first aforesaid adjustment serving to open the magnet circuit where closed thereby in said alternative adjustment of the switching mechanism.

All of the electro-magnetic equipment of each action and the gong or chime to be operated thereby is desirably mounted upon a single base which is made in separable sections that hermetically enclose a space containing the switching mechanism that is in control of the electro-magnetic mechanism.

I will explain my invention more fully by reference to the accompanying drawings showing the preferred embodiment thereof and in which Fig. 1 is a plan view of my improved electric action and a gong or chime to be operated thereby; Fig. 2 is a sectional view on line 2—2 of Fig. 1; and Fig. 3 is an electrical diagram illustrating the circuit connections of the equipment.

Like parts are indicated by similar characters of reference throughout the different figures.

The vibrating element illustrated is in the 100 form of a tubular gong or chime 1 having a bail 2 passing diametrically through its

upper end, this bail being carried by a hanger 3 adjustable longitudinally of a supporting frame 4 and held in adjustment by bolts 4'. The force with which the hammer 5 is applied to the vibrating element, in heavy actions, is sufficiently powerful to effect a partial rebound of the hammer from the vibrating element whereby the vibrations which are set up therein are not damped. The hammer is desirably electrically operated to effect both its striking and withdrawing movements and on this account I employ a striking winding 6 and a restoring winding 7 desirably forming the component 10 solenoids or magnets of a double magnet or compound solenoid having a common iron core 8 to be magnetically actuated by the windings, the striking coil 6 operating to move the core from its rearmost position 15 when the hammer 5 is to be applied while the restoring coil 7 operates to place the core together with the hammer adjacent thereto in a fully restored position. The hammer and the hammer stem 9 that couples the 20 hammer with the solenoid core are desirably made of brass, the hammer and its stem being coupled by a pin 10 that is downwardly projected to be in actuating relation to the intermediately pivoted rocker or switch arm 25 11 which is in fixed relation to a circuit closing blade 12 that is oscillated to correspond to the oscillating movements of the rocker arm 11. The switch blade 12 is always engaged by a common return contact 13. When 30 the hammer is brought to its retracted position said switch blade also engages a preferably bifurcated contact 14, and when the hammer is moved forward to a striking position said blade is separated from contact 35 14 and engages a contact 15, the blade separating from either contact 14 and 15 when being brought into engagement with the other. The shifting of the contact blade is concurrent with the shifting of the rocker arm 11, the latter being rocked in a counter clockwise direction by the pin 10 just before the hammer strikes the gong or chime, said rocker arm being brought to the reverse position illustrated when the hammer is fully 40 retracted. Thus the hammer when in striking movement closes one gap 12, 13, 15, in a master restoring circuit and in its withdrawing movement closes one gap 12, 13, 14, in a master striking circuit, the master circuits respectively including relays 16 and 45 17 which are respectively restoring and striking relays. In the embodiment of the invention illustrated each pair of these relays is governed by a key controlled switch, 50 there being illustrated a self-restoring piano key 18 governing a switch 19, 20 individual to the pair of relays 16, 17 and a testing switch 21, 22 in multiple with switch 19, 20 and positioned where the chime is located 55 to be accessible to one adjusting the chime

action. Reference hereafter will not be made to control switch 21, 22 as its effect is the same as that of switch 19, 20.

When the key 18 is depressed a circuit is established which is traceable from the positive pole of the generator 23 through the common conductor connecting this generator pole with the common contact 13, the switch blade 12, the bifurcated contact 14, the normally engaged contacts 24 and 25 of a striking switch which is individual to the striking relay 17, the winding of said striking relay, to the negative pole of said generator by way of the closed contacts 19 and 20 pertaining to the actuated key 18. The relays 16, 17 are desirably in the form of solenoids whose cores respectively carry contacts 26, 27. When the striking relay is energized the contact 27 upon its core is engaged with the contact 28 constituting one terminal of the winding 6 with the result that a hammer operating circuit is closed for imparting a striking movement to the hammer, such circuit being traceable from the positive pole of the generator 23, through the contacts 26, 27, the contact 28 engaged by the contact 27, the striking winding 6, to the negative terminal of the generator. When the striking winding is thus included in circuit the hammer is moved rapidly forward to strike the gong or chime 1, the hammer rebounding a slight distance and remaining in its rebounded position if the key 18, in the meantime, should happen to be released. Inasmuch as it is usual to maintain the actuated key depressed a sufficient length of time to bring the apparatus to normal or idle adjustment, circuits and circuit changes are brought about, when there is such continued depression of said key, and upon the hammer 5 nearly reaching its foremost position, in arriving at which position the pin 10 causes counterclockwise movement of the rocker arm 11 consequent upon engagement of said pin with the left hand end of said rocker arm. The switch blade 12 is consequently moved out of engagement with the bifurcated contact 14 and into engagement with the contact 15 constituting one terminal of a magnet 29. The circuit of winding 17 is thus broken, allowing switch 27, 28 to open to thereby cause deenergization of the winding 6, and another circuit is simultaneously established traceable from the positive pole of the generator 23, through the common conductor connecting this pole with the common contact 13, thence through the switch blade 12, the contact 15, the winding of magnet 29, the winding of restoring relay 16, thence to the negative pole of said generator, the key 18 being still depressed as stated. Thus it will be seen that the solenoid 6 is deenergized somewhat in advance of the hammer striking the chime and that the magnet 29 is energized before

the hammer reaches its foremost position, the hammer being carried forward by its momentum. It will also be noted that immediately upon energization of the magnet 5 the armature 29' thereof, which is pivoted at 29^a, is attracted and as a result the switch 31, 32 is closed and switch 24, 25 opened due to the inherent resiliency of member 25. The restoring relay 16, being now energized, applies the contact 26 upon the core thereof to the contact 20 and thereby closes the circuit of the restoring solenoid winding 7 (into whose bore the hammer core 8 extends), the circuit established by the engagement of the contact 26 with the contact 30 being traceable from the positive pole of the generator 23, through the contact 26, the contact 30, the restoring winding 7, to the negative terminal of said generator. Upon 10 energization of the solenoid 7 the hammer is retracted and when the same nears its rearmost position the pin 10 is brought into rocking engagement with the rocker arm 11 to move the switch blade 12 in a clockwise direction thereby to separate the switch blade 12 from the contact 15, a separation that would serve to open the circuit of the magnet 29 had not the attracted armature of this magnet caused the movement of the contact 31 into engagement with the contact 32, these latter contacts being respectively multiples of the contacts 13 and 15 and therefore serving as a holding switch to maintain the circuit of magnet 29 closed after the 15 switch blade 12 has been separated from the contact 15. As a consequence of the continued energization of the magnet 29 following the separation of the switch blade 12 from the contact 15 that occurs before the hammer reaches its rearmost position, the striking switch 24, 25 remains opened so that the striking relay 17 cannot be energized to engage its contact 27 with the contact 28, it being understood that the key 18 20 still continues to be depressed in order to maintain the energization of the magnet 29 whose circuit includes the switch 19, 20 controlled by such key. After the switch blade 12 has separated from the contact 15 it engages the bifurcated contact 14 to connect the positive pole of the generator 23 with the striking switch contact 24 so that when the actuated key 18 is finally released ultimately to open the circuit of the magnet 29 25 at the switch 19, 20, the armature of said magnet will be released, this armature being desirably forcibly retracted by the retractile spring 33 to remove it from engagement with the contact 31 and to bring it in such 30 forceful engagement with the contact 25 as to overcome the resilience of this contact and force it into engagement with the contact 24. Upon engagement of these contacts 24, 25, one gap in the circuit of the striking relay 35 17 is closed to enable the subsequent com-

plete closure of this circuit when the key 18, individual to this striking relay is depressed with the results which have hitherto been described.

The switch 31, 32, in addition to co-operating with switch 19, 20 to maintain the magnet 29 energized to keep the switch 24, 25 opened and the solenoid 7 deenergized to prevent chattering movement of the hammer against the chime, also maintains closed the circuit of the restoring relay 16 with whose winding said switch 31, 32 is in series and inasmuch as the restoring switch 31, 32 is not opened by the hammer but is only opened when the key 18 is released, the hammer may be placed in its fully withdrawn position providing the key 18 is maintained depressed a sufficient length of time.

It will be observed that the winding 16 is energized by two circuits, one of which, that is, the circuit including switch 12—13—15, may be termed the main operating circuit of electro-magnetically operated switch 26, 30, while the other, that is, the circuit including switch 31, 32, may be termed a secondary circuit therefor. Both include the winding 16 and the latter or secondary circuit is closed during retraction of the hammer and after the main circuit is opened by retractive movement of the hammer to thereby maintain the winding 16 energized and the hammer thereby retracted until the control switch constituted by 19, 20 is opened.

It will be further noted that the switch elements 31 and 32 when closed constitute with their continuing connections a shunt circuit which cuts in automatically when the main operating circuit of switch 26—30 is opened by retractive movement of the hammer to provide the closed secondary operating circuit of the switch 26—30 for continuing the activity of the electro-magnetic hammer retracting mechanism until the control switch 19—20 is opened.

Referring more particularly to Figs. 1 and 2, the supporting frame 4 is made with a separable portion 4² constituting a lid or closure for the pocket 4³ formed in the body of the support, bolts 4⁴ being employed to clamp the closure and the body portion of the support together. The support is desirably made of iron, the meeting edges of the closure with the marginal edges of the pocket 4³ being accurately machined to have tight hermetic fit. The electro-magnetic equipment is desirably supported upon the top or outer side of the closure 4² and the switching mechanism that controls such equipment is desirably confined within the pocket 4³ to be thoroughly protected from the elements. This switching mechanism is preferably fastened to the inner side of the closure.

While I have herein shown and particu-

larly described the preferred embodiment of my invention I do not wish to be limited to the precise details of construction shown as changes may readily be made without departing from the spirit of my invention, but having thus described my invention I claim as new and desire to secure by Letters Patent the following:

1. Sound producing mechanism including a vibrant element, a projectile and retractable hammer mounted to strike said element when projected, a control switch operable independently of electro-magnetic force, normally inactive electro-magnetic mechanism for initiating projection of the hammer, said electro-magnetic mechanism being rendered active by the closing of said control switch, normally inactive electro-magnetic mechanism for retracting and holding said hammer retracted, means operated by the final movement of projection of the hammer to render said first named electro-magnetic mechanism inactive and said second named electro-magnetic mechanism active, and means for maintaining the activity of said second named electro-magnetic mechanism until the control switch is opened.
2. Sound producing mechanism including a vibrant element, a projectile, and retractable hammer mounted to strike said element when projected, a control switch operable independently of electro-magnetic force, normally inactive electro-magnetic mechanism for initiating projection of the hammer including a circuit, a normally open electro-magnetically closed switch in said circuit, an operating circuit for said electro-magnetically operated switch including said control switch operable when closed to render the hammer projecting electro-magnetic mechanism active, normally inactive electro-magnetic mechanism for retracting and holding said hammer retracted, means operated by the final movement of projection of the hammer to render said first named electro-magnetic mechanism inactive and said second named electro-magnetic mechanism active, and means for maintaining the activity of said second named electro-magnetic mechanism until the control switch is opened.
3. Sound producing mechanism including a vibrant element, a projectile and retractable hammer mounted to strike said element when projected, a control switch operable independently of electro-magnetic force, normally inactive electro-magnetic mechanism for initiating projection of the hammer, said electro-magnetic mechanism being rendered active by the closing of said control switch, normally inactive electro-magnetic mechanism for retracting said hammer including a circuit, a normally open electro-magnetically closed switch in said circuit, an operating circuit for said elec-

tro-magnetically operated switch including the control switch, means operated by the hammer during its final movements of projection and retraction to close and open, respectively, the operating circuit of said electro-magnetically operated switch when the control switch is closed, and means for maintaining the electro-magnetically operated switch closed after the circuit thereof is opened by the movement of the hammer and until said control switch is opened.

4. Sound producing mechanism including a vibrant element, a projectile and retractable hammer mounted to strike said element when projected, a control switch, normally inactive electro-magnetic mechanism for initiating projection of the hammer, said electro-magnetic mechanism being rendered active by the closing of said control switch, normally inactive electro-magnetic mechanism for retracting said hammer including a circuit, a normally open electro-magnetically closed switch in said circuit, a main operating circuit for said electro-magnetically operated switch including the control switch, a shunt circuit, means operated by the hammer during its final movements of projection and retraction to close and open, respectively, the main operating circuit of said electro-magnetically operated switch when the control switch is closed, and means for maintaining the electro-magnetically operated switch closed after the main operating circuit thereof is opened by the movement of the hammer and until said control switch is opened, means for cutting in said shunt circuit during retraction of the hammer to provide a secondary closed operating circuit for the electro-magnetically operated switch until the control switch is opened.

5. Sound producing mechanism including a vibrant element, a projectile and retractable hammer mounted to strike said element when projected, a control switch, normally inactive electro-magnetic mechanism for initiating projection of the hammer, said electro-magnetic mechanism being rendered active by the closing of said control switch, normally inactive electro-magnetic mechanism for retracting said hammer including a circuit, a normally open electro-magnetically closed switch in said circuit, a main operating circuit for said electro-magnetically operated switch including the control switch, a shunt circuit including a normally open switch device, means operated by the hammer during its final movements of projection and retraction to close and open, respectively, the main operating circuit of said electro-magnetically operated switch when the control switch is closed, electro-magnetically operated means included in the main operating circuit of the electro-magnetically operated switch for closing the switch device of the shunt cir-

cuit to provide a secondary closed operating circuit for the electro-magnetically operated switch after its main operating circuit has been opened by retractive movement of the 5 hammer and until the control switch is opened.

6. Sound producing mechanism including a vibrant element; a hammer mounted to strike said element to set it into vibration; 10 electro-magnetic mechanism having a striking winding for moving the hammer into striking engagement with said vibrant element and a restoring winding for withdrawing the hammer to initial position; a striking 15 relay having a switch controlled thereby that is in the circuit of the striking winding for rendering the striking winding effective or non-effective; a restoring relay having a switch controlled thereby that is in the circuit of the restoring winding for rendering the restoring winding effective or non-effective; a normally open switch in the circuit of the restoring relay; a normally closed switch in the circuit of the striking relay; 20 an electro-magnet controlling the latter two switches and serving when energized to at-

tract its armature to open said normally closed switch and to close said normally open switch which is also in the circuit of said magnet to constitute a magnet holding 30 switch; a controlling switch in controlling relation to said magnet; and switching mechanism placed in one adjustment by the hammer in being restored and then serving to connect the aforesaid normally closed switch in the circuit of the striking relay and serving in an alternative adjustment that is effected by the hammer in being moved to striking position to disconnect said normally closed switch from the striking relay and to 35 close the circuit of said magnet to open said normally closed switch and to close said normally open switch, said switching mechanism in its first aforesaid adjustment serving to open the magnet circuit where closed 40 thereby in said alternative adjustment of the switching mechanism. 45

In witness whereof, I hereunto subscribe my name this 26th day of March A. D., 1920.

FREDERICK B. LITTLE.
